GRAB WINCH

Hermann Engler, Duisburg, Germany, assignor to Demag Aktiengesellschaft, Duisburg, Germany

Application July 25, 1931, Serial No. 553,093

3 Claims. (Cl. 254—184)

The invention relates to a grab winch provided with one-lever control.

The apparatus according to the invention has the advantage that the movements of the control lever are not co-ordinated with the movements of the drums as is customary, but with the movements of the grab; thus whereas at present one movement controls the hoisting drum and the other controlling movement controls the grab-operating drum, the operator can with apparatus according to the invention raise and lower the grab with one movement of the lever and open and close the grab with the other. By this means he is able to control the winch more effectively than heretofore and the work is not so strenuous as at present.

The control according to the invention may be employed with every known type of grab winch.

The accompanying drawing illustrates by way of example one construction of apparatus according to the invention, that is to say the combination of one-lever control with a differential grab winch. By the latter term are meant grab winches with two drums and two motors in which one motor, acting as a hoisting motor, drives both drums, while the smaller or grab-operating motor is connected to one drum only and its movement is superposed over that of the hoisting motor by means of a differential or planetary gear.

In the accompanying drawing Figure 1 is a diagrammatic representation of a lay-out of mechanism according to the invention, and Figure 2 is a sectional view of the planetary gear.

The winch illustrated in the drawing is controlled by means of the control lever 1; this lever primarily moves in a plane perpendicular to the plane of the paper and thus rotates the spindle 2. A bevelled gear wheel 3 is mounted on the spindle 2 and engages in the bevelled gear wheel 4 which in turn is mounted upon the rotating shaft of the controller 5. The controller 5 is connected to the motor 7 through the leads 6. Thus the movement of the lever perpendicularly to the plane of the paper controls the raising and lowering of the grab.

The lever 1 can also move in the plane of the paper about the pivot 8, as shown by the arrow across the handle, namely, into the two positions 8a and 8b, which are only a short distance from the central position. When making these movements the lever strikes against the contact stops 9, which are connected through the leads 10 to an automatic starter 11 of known construction.

The starter controls the grab-operating motor 13 through the leads 12.

A clutch 14 of known type is mounted on the shaft 7a of the motor 7; the cylindrical surface of the clutch acts in known manner as the braking surface of a brake 15. The pinion 16 on the motor shaft 7a engages in the toothed periphery 17 of an annular sun wheel of a planet gear, a second set of teeth 18 being cut into the inner side of the said sun wheel. This second set of teeth is in engagement with the planet pinions 20, which are mounted on the carrier 21. A pinion 22 is secured to the carrier 21, and at the same time is engaged with the drum gear wheel 23 of the grab-operating drum 24; the opening and closing ropes of the grab are wound around the grab-operating drum 24.

The motor shaft 7a also carries a pinion 25, which engages in the gear wheel 26. Mounted on the shaft 26a is a pinion 27, which is in engagement with the drum wheel 28 of the hoisting drum 29.

The shaft 13a of the grab-operating motor 13 is similarly provided with a clutch 30 whose outer surface acts as the braking surface for the brake 31. Upon the extension 32 of the shaft 13a is mounted the sun pinion 33 of the planet gear, which pinion engages with the planet wheels 20.

The apparatus operates as follows:

If the lever 1 is moved in the direction perpendicular to the plane of the paper, the motor 7 is put into operation; the brake 31 is then effective, and thus the sun pinion 33 is stationary. The motor 7 through the gear wheel 16 drives the toothed periphery or sun wheel 17 of the planet gear, which drives the planet wheels 20. These wheels rotate around the braked sun pinion 33 and thus move the carrier 21. As the carrier 21 is connected to the pinion 22 and the latter engages with the gear wheel 23 the drum 24 is rotated. Furthermore, the motor 7 drives the hoisting drum 29 through the wheels 25, 26, 27 and 28.

If the lever 1 is moved in the plane of the paper, the motor 13 is caused to rotate under the action of the automatic starter 11. The motor 7 may then be stopped by the brake 15, and with it the gear wheels 25, 26, 27 and 28, and the hoisting drum 29 and also the toothed periphery or sun wheel 17, 18. If the motor 13 is operative and the brake 31 is released, the shaft 32 and the sun pinion 33 are rotated and the planet wheels 20 travel around the internal toothed periphery 18, and thus drive the car-

rier 21 and, through the gear wheels 22, 23, the locking drum 24. If both motors are running their two movements are superposed, that is to say the locking drum 24 rotates more rapidly or 5 more slowly than the locking drum 29, so that the grab is opened or closed by the drum 24 during raising or lowering. The complete gearing, with the exception of the reduction gear of the drums, is enclosed in the casing 34.

10 I claim:

1. A single lever control for a two-drum grab winch comprising a hoisting motor, a hoisting drum and a grab-operating drum both driven from said hoisting motor, a grab-operating motor for driving said grab-operating drum, and planet gearing connecting said hoisting motor and said grab-operating motor with said grab-operating drum whereby the drive of the latter motor may be superposed upon that of the former motor, said control consisting of a lever element movable about two axes disposed at an angle one to the other, electric control means for the hoisting motor and electric control means for the grab-operating motor, the said control 15 means for the hoisting motor being operated independently by movement of the lever element about one axis and the control means for the grab-operating motor being operated independently by movement of the lever element about 20 the second axis into either of two limiting positions.

2. In a single lever control for a two-drum grab winch according to claim 1, the provision of fixed contacts disposed at opposite sides of 25 the lever element and positioned at a short distance apart for engagement respectively by the lever element in its movements in opposed directions about the said axis, the said contacts

extending parallel to the directions of movement of the lever element about the first axis sufficiently to permit the lever element to contact therewith at any required position of the movements about the first axis, the said contacts serving electric circuits for the control of the operation of the grab-operating motor.

3. A single lever control for a two-drum grab

80

winch comprising a hoisting motor, a hoisting drum and a grab-operating drum both driven from said hoisting motor, a grab-operating motor for driving said grab-operating drum, and planet gearing connecting said hoisting motor and said grab-operating motor with said grab-

85

operating drum whereby the drive of the latter motor may be superposed upon that of the former motor, said control consisting of a lever element, a spindle upon which said lever element is pivoted for restricted movement in a plane containing the spindle, the said spindle being rotatably mounted, an electric controller for said hoisting motor, said electric controller comprising movable and fixed elements, transmission mechanism between said lever element and said movable element of the controller for

90

imparting movement to the latter from the former, and contacts disposed in fixed position and on opposite sides of said lever element to co-

95

operate therewith in the restricted movement about the pivotal axis upon the spindle, said contacts extending in parallel positions transverse to the axis of the spindle for engagement by the lever element at any position of its move-

100

ment of rotation of the spindle and serving electric circuits for the control of the operation of the grab-operating motor.
